EMERGENCY ROAD FLASHER

Leonard Osrow, Glen Cove, N.Y., assignor to Osrow Products Company, Inc., New York, N.Y., a corporation of New York

Filed Aug. 7, 1969, Ser. No. 18,571

Term of patent 3½ years

Int. Cl. D29—99

U.S. Cl. D72—1

FIG. 1

FIG. 2

FIG. 3

FIG. 4

FIG. 5

FIG. 1 is a front perspective view of an opened emergency road flasher showing my new design;

FIG. 2 is a rear perspective view thereof on a greatly reduced scale;

FIG. 3 is a side view thereof on a reduced scale;

FIG. 4 is a rear elevational view of the flasher in the collapsed position;

FIG. 5 is a bottom plan view thereof on an enlarged scale.

The cord is fragmentarily shown in FIGS. 2 through 5 for convenience of illustration.

I claim:

The ornamental design for an emergency road flasher, substantially as shown and described.
